SLIP CONSTRUCTION

Frank Kopp, Brooklyn, and Lewis Morris, Mount
Vernon, N. Y.

Application April 7, 1937, Serial No. 135,427

1 Claim. (Cl. 2-73)

This invention relates generally to ladies' garments and has reference more particularly to undergarments such as slips, chemises and the like.

Undergarments of the character indicated require, among other essential features, a snug fit to the contour or curves of the body, particularly the upper portion of the torso or bust, thereby enhancing the appearance of the outer garment 10 in conformity with the dictates of modern style.

Accordingly, one of the objects of this invention is to attain such features of form fitting in a garment with maximum ease and comfort to the wearer, by providing an undergarment which embodies a simple and novel assemblage of material and parts so as to present a continuous curved line across the waistline with increasing flare towards the bottom, thus producing a molded effect, the characteristics of which are flatness across the abdomen and freedom of bulging at the back.

Another object is to provide a lady's garment having a bust portion or brassière section of a firm substantial non-stretching structure which will give the desired support for the bust without interfering with the proper fit of the body.

A further object is to provide a lady's undergarment in which the various parts have been so cut and assembled as to afford sufficient elasticity to accommodate with ease the body of the wearer and to prevent wrinkling or bulging, particularly at the front and back, respectively.

Still another important object of the invention is to provide a garment including a waist or bust portion having elastic or contractible means so constructed and arranged therein that the snug fitting of the garment and the desired support for the bust is assured notwithstanding a normal loss or gain in weight of the wearer.

Other objects and advantages will be apparent as the specification proceeds. The invention will be fully and comprehensively understood from a consideration of the following detailed description when read in connection with the accompanying drawing which forms a part of the application.

In the drawing:

Figure 1 is a perspective view illustrating the front portions of the undergarment embodying the invention.

Figure 2 is a fragmentary perspective view similar to Figure 1 but showing the rear portion of the garment.

Figure 3 is a fragmentary front elevational view of the upper portion of the garment illus-

trating the construction of the bust portion thereof, and

Figure 4 is a fragmentary elevational view showing the back portion of the garment.

Referring now to the accompanying drawing 5 for a more detailed description thereof, the numeral 5 indicates generally the body portion of the undergarment which, in the preferred concept of the invention, defines a waist and integral skirt portion. It will be observed that the 10 garment may, if desired, define merely a skirt, waist or brassière by the omission of the depending skirt portion, in which instance the body portion 5 may terminate at or adjacent the waistline of the wearer.

The body portion 5 may be fabricated in any suitable manner but preferably includes a front section 6 and a rear section 7 joined at corresponding edges by suitable means, as by stitching along the lines 8 so as to form a tubular structure to surround or partially encircle a portion 15 of the wearer's body.

The front section 6 has the top portion thereof tapered to define upwardly convergent edges 9 preferably terminating in an apex 10. A pair of breast panels 11 is provided, each panel being cut to define substantially a rectangular outline such, for example, as a diamond shape, and each panel 11 is assembled into the garment by joining corresponding edges of the respective 20 panels to the convergent edges 9 of the front section 6.

In order to provide fullness in the intermediate area of panel 11 so as to conform to the bust of the wearer, the junctural edges of each panel 11 25 are Shirred or gathered as shown. This operation may be accomplished during the stitching together of the mentioned parts. Although the panels 11 are preferably patterned in a rectangular outline so as to define a V neck having its 30 apex at the point 10, it will be apparent that the upper edges of the panels 11 may be shaped in any desired manner so as to suitably support the garment by means of the shoulder straps 12, or the like, having their corresponding ends affixed 35 to the respective panels 11, their ends being joined to the back of the garment.

In the fabrication of this undergarment, certain characteristics of cloth materials affording elasticity are employed to accomplish particular 40 advantages. For example, substantially the entire body portion 5, including the front panel 6 and the back panel 7, is cut from the stock material on the bias or diagonally of the warp and weft of the material, so that the composite skirt 45

or body portion assumes a tubular structure having substantial elasticity laterally and vertically of the garment to accommodate itself somewhat to the size and shape of the wearer's body 5 as well as to permit distortion of the garment, as during motions of the body.

In order to provide better support for the bust and to prevent improper distortion, the breast panels 11 are cut straight along the warp threads 10 of the material to form rectangular patterns, one corner of which is connected to the shoulder strap 12. It will thus, be seen that when the breast panels 11 are joined to the body portion along the edge 9, the grain of the breast panels 15 11 will run substantially parallel with the grain of the bias cut front panel 6.

Certain economies in the amount of material required in the garment will also result in this construction. The cutting of the panels 11 as 20 described is preferable, particularly in order to assure a substantial non-stretching effect along the seam 9 for reasons hereinafter described. On the other hand, some elasticity will be afforded in the direction of the arrows in Figure 3.

25 It will be noted that the axis of the distortion will also become centered in the breast panels due to this construction so that uniform tension across the bust will be assured at all times, irrespective of the movement of the wearer.

30 The back panel 7 of the body portion 5 terminates at the upper edge thereof in a substantially straight line 13 to which edge is connected a yoke 14. As mentioned, the back panel 7 is preferably cut from material set on the bias.

35 The yoke member 14 on the other hand, is cut along the warp or weft of the material so as to reinforce the edge 13, as well as to afford a non-stretching structure encircling the bust of the wearer. The arrangement of this panel in addition

40 makes the garment curve into the hollow of the back, thus enhancing the molded effect and preventing bulging. The opposed ends of the yoke 14 are suitably joined to corresponding portions of the breast panels 11. The yoke 14 is 45 preferably gathered at suitable regions so as to accentuate the form fitting characteristics of the garment.

Ordinarily, a garment which is too form fitting interferes with the comfort of the wearer and, 50 therefore, does not find much favor with women despite the constant desire to present a slender appearance.

This object has been overcome by a feature in 55 the invention which will be presently described. This novel feature will impart sufficient yieldability to the garment so that it will fit snugly and still comfortably, even though the garment may be considerably oversized or undersized for 60 the particular wearer.

The aforementioned object is accomplished by cutting out portions and inserting contractile or elastic members 15 in the cut-outs at each side of the garment. It will be noted that these members 15 are so constructed and arranged that they will cooperate with the various other parts making up the garment to obtain the desired result.

The members 15 are preferably of an elongated 65 ovoidal pattern, tapering to points 16 and 17 at 70 each end and made of an elastic material, such

as rubber woven fabric. The point 16 joins with the seam 18 connecting the panel 11 with the yoke 14, and the point 17 joins with the seam 8 connecting the front and rear panels 6 and 7.

This arrangement and construction provides 5 for the greatest degree of elasticity across the abdomen and along the convergent lines 9, thus giving the brassière section an "up-lift" effect at the same time as it brings the waistline of the garment into close, yet yieldable fit with the body 10 of the wearer.

The molded effect of the garment is enhanced by the draping of the body portion 5 from the apex 10 which will have a natural tendency to pull in the waistline while increasing the flare 15 at the bottom.

It will also be noted that because of the particular construction of the elastic member 15, the straight-cut panels 11 and the bias-cut body portion 5 with the apex 10, the tension across the 20 bust will always be uniform irrespective of the movements of the wearer.

Although the use of both bias-cut and straight-cut fabric on the same garment is old in the art, the present invention contemplates broadly the 25 combination of these fabrics in such a manner that the maximum of support for the bust will be produced while at the same time making the garment sufficiently yieldable to insure comfort to the wearer.

30 The disclosure specifically described and illustrated embodies the essential and distinct thought and concept which characterizes the invention, but it is to be understood that the same may be combined with various other concepts or details 35 without affecting the peculiar results obtained, and that changes and modifications may be resorted to without departing from the spirit or the scope of the appended claim.

40 What is claimed is:

A form fitting lady's undergarment comprising a brassière section and a body section, said body section consisting of a front panel and a rear panel, said front panel having upwardly convergent edges, said brassière section consisting of a 45 pair of breast panels of substantially rectangular outline, each secured to said front panel along said convergent edges so as to jointly define a V neck opening, a yoke member bordering the top edge of said rear panel and connecting said breast panels whereby a firm support for the bust will be provided and distortion prevented, means for uniformly tensioning said brassière section and the waist portion of said body section about the wearer, said means comprising a pair of 50 elastic members each interconnecting all of said front and rear panels and said breast panels and said yoke member, said members being of elongated ovoidal shape tapering into points at the opposite ends merging with the seam interconnecting said front and rear panel adjacent the armpit and the waist respectively, and above and below said convergent edges, their widest portion being substantially between the seams connecting said rear panel and said yoke member and the seam connecting said convergent edges whereby the greatest degree of elasticity will be 55 along said convergent edges and across the abdomen of the wearer.
